ASSIGNORS, BY MESNE ASSIGNMENTS, TO ASSOCIATED ELECTRIC LABORATORIES
INC., OF CHICAGO, ILLINOIS, A CORPORATION OF DELAWARE

AUTOMATIC TELEPHONE SYSTEM

Application filed January 7, 1929, Serial No. 330,843. Renewed September 14, 1931.

The present invention relates in general to multi-office telephone systems, but is concerned more particularly with telephone systems in which calls are extended through the medium of automatic switches. The main features of the invention relate to multi-office systems in which a calling subscriber may be charged for completed calls according to the actual duration of the call and also according to the location of the office or exchange in which the called line terminates.

In multi-office telephone systems it is sometimes desirable to make a fixed charge for completed calls within an exchange or between several exchanges relatively near together in the same area or zone, while calls from exchanges in one zone to exchanges in a different zone may be charged for on the basis of the duration of the call.

A suburban service may be provided whereby calls will be extended directly by a manual operator to a subscriber in a semi-distant exchange without setting up the usual toll connections. It is customary to make a greater charge for calls of this type than is made for calls between subscribers in the same town or system of exchanges. The additional charge may be made by keeping a written record of each call or by providing a means by which the operator may cause the subscriber's meter to register additional call units. The latter method is preferable as it eliminates the necessity of verifying the number of the calling line.

The present invention is particularly effective in a system of the above type, as it provides for automatically registering the proper charge for local and inter-zone calls, and also provides a simple means whereby an operator may make an additional charge on suburban calls.

One object of the invention is to improve systems of this general character by providing simplified circuits by which the metering operation may be accomplished.

Another object of the invention is to provide circuits whereby calls may be extended automatically from one exchange to another through an intermediate exchange, the metering operation being effected by apparatus in

the intermediate exchange which in turn is controlled from the terminating exchange.

Another object of the invention is to provide a means whereby an operator at a manual or toll board may position the repeater through which a call is extended from an outlying exchange so that meter registrations will automatically be increased when the call is further extended to a semi-distant exchange.

Other features of the invention relate to the provision of various circuits in a system of this kind tending to make it more efficient and practical.

The foregoing features together with others not specifically mentioned will be more fully pointed out hereinafter.

The accompanying drawings comprising Figs. 1 to 9, inclusive, show by means of the usual circuit diagrams, a sufficient amount of equipment in a telephone system embodying the features of the invention to enable the invention to be understood.

For the purpose of this description it is assumed that the equipment embodying the invention is located in three separate exchanges which will be designated as offices X, Y and Z, respectively. It is to be understood, however, that the application of the invention is not limited to this particular arrangement but that it may be used with other combinations of equipment and in systems comprising a different number of exchanges from that described herein.

Fig. 1 and that portion of Fig. 2 lying to the left of the heavy broken line show equipment located in X office. Fig. 2 to the right of the heavy broken line and Figs. 3, 4, 6 and 7 show equipment located in Y office. The equipment in Z office is shown in Fig. 5. Fig. 8 shows the method of strapping the test contacts of the banks of switching connector C of Fig. 1. Fig. 9 is a layout diagram showing how the sheets on which Figs. 1 to 7, inclusive, are drawn should be placed together in order to be understood best.

Referring particularly to Fig. 1, A and A₁ represent ordinary automatic substations equipped with the usual talking, signalling

and impulsing instrumentalities and individually connected to line switches LS and LS₁, respectively. The line switches are of the well known rotary type provided with a meter controlled over a separate wiper of the switch.

Mechanically, connector C is of the well known Strowger vertical and rotary type. The circuit is similar to the ordinary switching rotary connector with modifications to provide a quick switch-through on trunk calls. This feature is superior to the switching-through methods used in previous connectors since the quick connection to the succeeding switch minimizes the chances of mutilating or losing a dialed digit which might occur in case of delay in extending the trunk.

In Fig. 2 is shown an outgoing repeater OR and an incoming connector C₁ associated with the end of a trunk terminating in X office. The incoming repeater IR and outgoing repeater OR₁ are associated with the other end of the trunk in Y office. The circuit of repeater OR is similar to the ordinary loop repeater modified by the addition of a relay whose function is to provide a special means of metering. Connector C₁ is identical with connector C. Only that part of the connector circuit associated with the cut-off relay of repeater OR has been shown in detail. Connectors C and C₁ are assumed to have access to the same group of subscriber's lines such as A and A'.

Repeater IR is normally connected to the trunk through contacts of the cut-off relay of repeater OR₁. This repeater is controlled by the loop circuit extended by repeater OR and in turn extends the connection to an incoming trunk switch. When a call extended through the repeater is answered, the operating loop circuit is switched to a simplex holding circuit. Metering impulses are repeated back to the calling line by removing the potential from the simplex holding circuit.

Repeater OR₁ is connected with the trunk only when a call is extended therethrough and in this case, repeater IR is disconnected from the trunk. Repeater OR₁ extends a loop circuit over the trunk to operate connector C₁ in the usual manner. This repeater is also arranged for metering over the fourth conductor of the incoming trunk.

Referring to Fig. 3, incoming selector S is an ordinary Strowger type selector provided with a separate conductor and wiper for metering purposes. This selector is in the same office and is directly associated with incoming repeater IR. The loop extended by the repeater controls the operation of the selector in the usual manner, and when an idle trunk is found, the loop is extended to the succeeding switch free of any connections in the selector.

Fig. 4 shows an outgoing repeater, OR₂,

and an incoming repeater IR₁ associated with a two way trunk. These switches are assumed to be in Y office, the associated trunk extending to Z office. Repeater OR₂ is accessible to both local and incoming selectors in Y office. Associated with and a part of repeater OR₂, is a time pulse metering device M consisting of a rotary switch RS and associated relays. On calls extended through the repeater, the operation of the time pulse device under control of the interrupter INT causes metering impulses to be transmitted back to the calling line at certain preestablished intervals. On calls to an operator the rate at which metering pulses are sent out can be increased to twice the normal rate under the control of the operator. As shown, the repeater is normally disconnected from the trunk, but when a call is extended thereto, the cut-off relay of the repeater transfers the trunk from incoming repeater IR₁ to repeater OR₂.

Repeater IR₁ is a simple repeater operating over a loop to which battery and ground are connected at the distant office. The repeater extends a loop to incoming selector S₁, and controls it in the usual manner. The circuit of selector S₁ is exactly the same as that of selector S shown in Fig. 3.

Fig. 5 shows equipment located in an exchange of the type in which dialed impulses are repeated by the first selector to succeeding switches of the train.

Incoming repeater IR₂, normally associated with the trunk operates over the loop extended by repeater OR₂ and extends a control circuit to selector S₂. Dialed impulses are repeated as ground impulses over a conductor of the trunk while a holding circuit is maintained over the other trunk conductor. When a call extended through the repeater is answered, a ground potential placed on one trunk conductor by the connector operates a relay in the repeater. This relay short circuits a part of the winding of the relay controlled by the loop from the preceding switch and thereby increases the current flow in the trunk. The increase in current flow is used to operate the metering equipment in the preceding switch.

Selector S₂ is mechanically similar to the previously described selectors S and S₁. The circuit, however, is of the well known type used in the system of Siemens & Halske.

Selector S₂ has access to the usual switch train in an office of this type comprising selectors S₅ and connectors C₃ which, being well known, will not be described in detail. Succeeding selectors may be identical with selector S₂. A connector which will operate satisfactorily in this system is shown on page 46 of the illustration section of Dr. Fritz Lubberger's book "Die Fernsprechanlagen

Mit Wähler-Betrieb (Automatische Telefonie)", third edition, 1926.

Selector S_2 also has access to trunks terminating in an operator's position, a part of the operator's answering equipment, OA, being shown. It is assumed that all toll and suburban calls for the system will be handled at this operator's position which is located in Z office.

- 10 An operator's calling circuit, OC, also has access to the trunk to which repeater IR_2 is connected. When the trunk is used by the operator the repeater is disconnected, and when the repeater is in use the operator's circuit is disconnected and the operator is informed by a usual visual signal of the busy condition of the trunk. Calls from substations such as A4 in Z office to substations in X and Y offices will be completed by the operator. The operator extends calls over the trunk by means of a loop to which battery and ground are connected at the manual position.

25 In Fig. 6, selector S_4 which is represented by a rectangle, is identical with selector S_1 . A_2 represents a substation in Y office terminating in rotary line switch LS_2 which in turn has access to selector S_4 . Substation A_2 and line switch LS_2 are exactly the same as previously described substation A and line switch LS.

30 In Fig. 7, C_2 represents a local connector of the ordinary Strowger type arranged for fourth wire metering. The connector is assumed to be in Y office and has access to subscriber's lines of which substation A_3 terminating in rotary line switch LS_3 is one. The connector is accessible in the banks of local selector S_4 and incoming selectors S and 35 S_1 all in Y office. Substation A_3 and line switch LS_3 are the same as previously described substation A and line switch LS.

40 The various units of equipment and their locations with relation to each other have been briefly described. The arrangement and operation of the system as a whole will now be considered.

45 Office X is assumed to be a branch exchange connected by means of two-conductor trunks with office Y, a main exchange. Office Y is provided with trunks to other main exchanges such as Z office. Inter-office calls originating in X office will be routed through equipment in Y office in a manner 50 commonly known as tandem trunking.

55 The equipment in X and Y offices is of the two-wire type in which the various switches are directly controlled by the calling subscriber over the two sides of the line in series. Equipment in the Z office is of the type in which the first selector only is directly controlled by the calling subscriber over the two sides of the line in series. Succeeding 60 switches are controlled by impulses repeat-

ed by the first selector and transmitted over one side of the trunk.

Calls may be completed automatically in and between X and Y offices and from either of these offices to Z office. Local calls in Z office may be completed automatically but calls from this office to either X or Y office are completed manually.

65 On calls in and between X and Y offices, one meter registration is made for each completed call regardless of duration. On calls from either of these offices to a subscriber in Z office, one meter registration is made as soon as the call is answered with an additional registration for each time unit over the basic time interval. The time interval may be set within any reasonable limit. Local calls in the Z office may be metered by any of the methods ordinarily used in exchanges of this type.

70 Suburban calls, that is, calls to subscribers in other nearby cities of this system or other systems are completed by a manual or toll operator in Z office. Calls of this class originating in X or Y offices are extended over the regular inter-office trunks and through the switch train at Z office to the manual or toll position. The operator may position the repeater at Y office through which the call was extended so that the metering charge ordinarily registered for calls to Z 75 office will be doubled.

75 Having explained the object of this invention and the apparatus employed, the operations involved in setting up various 80 connections in a system of this type will now be described in detail.

85 Assuming first that the subscriber at substation A (Fig. 1) in X office calls the subscriber A4 in Z office (Fig. 5). When the receiver is lifted at the substation A, the usual loop circuit is closed over the two conductors of the calling line and line switch LS searches for an idle trunk in the usual manner. When an idle trunk is encountered, 90 for example, the trunk comprising conductors 18 to 21, inclusive, the calling loop is extended to line relay 103 of connector C.

95 Line relay 103, release relay 104 and change-over relay 105 of the connector are 100 energized in the usual manner. Relay 104 connects ground to the release trunk at armature 130 to hold the cut-off relay of the line switch in operated position. Relay 104 also 105 closes a part of the impulsing circuit at armature 131. At contacts controlled by armature 132, relay 105 disconnects ground from the lower winding of relay 103 and connects thereto another ground on which the dial tone is superimposed. At armature 134 relay 105 connects the impulsing circuit to vertical magnet 112 and at armature 133 connects its own lower winding to the impulsing circuit in parallel with the vertical magnet. The foregoing operation takes place 110 115 120 125 130

when the receiver at the calling substation is lifted and the connector is then ready to receive the dialled impulses.

It will be assumed that the calling subscriber now dials the digit "0". The calling loop will be opened ten times and line relay 103 of the connector will respond by deenergizing and reenergizing with each interruption of the loop. With each deenergization of relay 103, the vertical magnet will operate in the usual manner and raise the shaft one step at a time until the wipers are opposite the tenth level of bank contacts. The initial energizing winding of relay 105 is short circuited at contacts 119 of the off-normal springs which closed on the first vertical step. Relay 105 does not deenergize at this time since its lower winding is connected in parallel with the vertical magnet and due to its slow releasing character, the ground impulses to the vertical magnet are sufficient to keep it energized during the period of impulsing. Shortly after the last impulse of the series, relay 105 deenergizes and disconnects its lower winding from the impulsing circuit at armature 133, and at armature 134 switches the impulsing circuit to rotary magnet 113. Upon restoring, relay 105 disconnects the ordinary tone ground and reconnects the ordinary ground to the lower winding of relay 103. Relay 104 being slow to release also remains energized during the series of impulses when its circuit is opened by the impulsing of relay 103.

As the wipers are stepped to the tenth level, the shaft springs operate and contacts 122 close a part of the circuit of relay 101, which, however, does not operate at this time. A part of the metering circuit is also opened by the shaft springs at contacts 121.

It will now be assumed that the tenth level of the connector banks is equipped with four trunks terminating in the repeaters such as OR, and that these trunks are connected to the first four sets of bank contacts of the level. The subscriber now dials the digit "1". Relay 103 responds in the usual manner and the rotary magnet is energized over a circuit including armature 131 of relay 104, armature 134 of relay 105, armature 143 of relay 108, winding of relay 109, and armature 157 of relay 111. Slow release relay 109 energizes in series with the rotary magnet and at armature 145 opens a point in the circuit of the lower winding of relay 110.

At armature 146 a circuit is closed for the upper winding of relay 110, and at armature 147 a point in the circuit of relay 107 is opened. The utility of the last operation will be described in more detail later on.

Relay 110 operates and at armature 148 closes a point in the circuit of its own lower winding; at armature 149 connects test wiper 117 to test relay 108; at armature 150 closes a point in the locking circuit of its own up-

per winding; at armature 151 closes a circuit for the rotary magnet independent of the contacts of the relay 108; at armature 152 closes a point in the circuit of relay 107; and at armature 153 opens a point in the busy tone circuit.

If the trunk on which the wipers stop is busy, test wiper 117 will find a ground potential. Test relay 108 will operate from this ground over a circuit including armature 149 of relay 110. Relay 108 upon operating closes a part of its own locking circuit at armature 141; at armature 142 completes a locking circuit for the upper winding of relay 110; at armature 143 opens a point in the circuit of the rotary magnet; and at armature 144 closes a point in the busy tone circuit.

Shortly after the rotary impulse, or after the last of the series if there be more than one, slow release relay 109 deenergizes. The lower winding of relay 110 is then connected to control wiper 118 by way of armature 145 of relay 109. Relay 110, however, has no function to perform at this time. At armature 146 relay 109 opens the initial energizing circuit of relay 110 and at armature 147 closes a circuit for relay 107 including armature 152 of relay 110 and the interrupter springs of the rotary magnet. Relay 107 operates and armature 139 closes a circuit for the rotary magnet including armature 157 of relay 111, and at armature 140 closes a locking circuit for itself including the interrupter springs of the rotary magnet. The rotary magnet energizes, steps the wipers to the next set of bank contacts, and opens the circuit of relay 107 at its interrupter springs. Relay 107 deenergizes, opens its own locking circuit, and opens the circuit of the rotary magnet which also deenergizes. If the next trunk is busy, the above described operation is repeated, relay 107 and the rotary magnet alternately energizing and deenergizing to step the wipers ahead a step at a time.

If all trunks of the group are busy, the wipers are stepped to the set of contacts following the last trunk of the group. In this case the bank contacts with which wipers 117 and 118 are engaged are strapped together and connected to ground as shown in Fig. 8. Relay 108 will remain energized from this ground over the test circuit previously traced. A current will also flow in the lower winding of relay 110 over a previously traced control circuit to ground over wiper 118. The two windings of relay 110 oppose each other and consequently the relay deenergizes very quickly when the control wiper encounters a ground. Relay 110 on deenergizing opens the circuit for both of its windings, completes a previously traced locking circuit for relay 108 including contacts controlled by armature 149 of relay 110 and armature 141 of relay 108, opens the circuit for relay 107 at armature 152 to prevent that relay from

again energizing and operating the rotary magnet, and at armature 153 closes a part of the busy tone circuit. The busy tone is now given to the calling subscriber who is therefore informed that all trunks are busy at this time.

If a trunk had been idle, for example, the trunk comprising conductors 167 to 170, inclusive, terminating in bank contacts 159 to 162, inclusive, the wipers would stop on these contacts, the operation being as follows:

An idle line is marked by battery potential on the test contacts. If the first trunk is idle, wiper 117 encounters the battery potential on the test contact and relay 108 does not operate. Shortly after the last rotary impulse, relay 109 restores. If, however, busy trunks had been tested previous to finding the idle trunk, relay 108 would be energized and relay 109 deenergized as previously described. Relay 108 then deenergizes when wiper 117 encounters the battery potential on the test wipers. With both relays 108 and 109 restored to normal, the circuit of relay 110 will be open and relay 110 deenergizes. A circuit may then be traced from battery on the test contact, wiper 117, armature 149 of relay 110, lower winding of relay 111, to ground at armature 130 of relay 104. Relay 111 operates over the above circuit and at armatures 154 and 158 connects the talking conductors of the connector to wipers 115 and 116; at armature 155 connects test wiper 117 to the release trunk; at armature 156 connects its own upper winding to the release trunk and closes a circuit for relay 101, including contacts 122 of the operated shaft spring, and opens the circuit of the rotary magnet at armature 157. The upper winding of relay 111 now maintains it in operated position. Relay 101 operates and, at contacts controlled by armatures 123 and 126, switches the conductors of the calling loop from relay 103 to wipers 115 and 116; at armature 124 connects meter conductor 21 to wiper 118; and at armature 125 opens a point in the circuit of the release magnet. After relay 101 operates, relays 103 and 104 deenergize. Relay 104 being slow to restore, will maintain the holding ground on the release trunk until a ground is returned by the switch ahead. These relays upon restoring also close points in the release circuit at armatures 129 and 131. The calling line loop is now extended directly to line relays 202 of the repeater OR by way of wipers 115 and 116, contacts 159 and 160, conductors 167 and 168, left hand windings of repeating coil R, and contacts controlled by armatures 212 and 213 of relay 201. Metering conductor 21 is extended by way of wiper 118, contact 162, and conductor 170 to a contact at armature 215 of relay 201.

Release trunk conductor 20 is extended by way of wiper 117, contact 161, conductor 169,

to contacts at armature 219 of relay 204, and thence through normally closed contacts 130' of relay 104' in incoming connector C1, to relay 205. Relay 104' corresponds with relay 104 of connector C. Relay 104 of connector C, as previously explained, has maintained a ground on release trunk for a short interval after the connection is extended. Relay 205 operates from this ground and switches trunk conductors 207 and 208 from the incoming connector C1 to talking conductors of the repeater OR.

Relay 202 energizes over the calling loop and at armature 216 closes a point in the loop circuit to the repeater IR in the distant office, and at armature 217 closes an obvious circuit for relay 204. Relay 204 operates and at armature 219 connects ground to the release trunk to hold the preceding switches in operated position and to keep relay 205 energized after relay 104 of connector C deenergizes. At armature 220 relay 204 also closes a circuit for the upper windings of relay 203 including armature 211 of relay 201, and a circuit for the lower winding of polarized relay 201 including resistance 206; and at armature 221 completes the loop circuit to the incoming repeater in the distant office. Relay 203 operates and opens a part of the metering circuit at armature 218. Relay 201 does not operate at this time due to the high resistance in the circuit.

Line relay 236 of incoming repeater IR operates over the loop circuit extended by the repeater OR. This circuit may be traced as follows: battery, upper winding of relay 236, contacts controlled by armature 245 of relay 234, upper left hand winding of repeating coil R1, armature 268 of cut-off relay 261 in repeater OR1, thence over the trunk conductor 207, armature 223 of relay 205 in repeater OR, armature 216 of relay 202, upper right hand winding of repeating coil R, upper winding of polarized relay 201, lower right hand winding of repeating coil R, armature 221 of relay 204, armature 224 of relay 205, thence over trunk conductor 208, armature 269 of relay 261, left hand winding of repeating coil R1, contacts controlled by armature 246 of relay 234, lower winding of relay 236 to ground. Relay 236 on operating closes a loop circuit to the succeeding switch at armature 248 and at armature 249 closes an obvious circuit for relay 231. Relay 231 operates and at armature 238 connects ground to release trunk conductor 252, a branch of which extends through the lower winding of polarized relay 235. Relay 235 does not operate at this time, however, over its lower winding alone. At armature 239 relay 231 disconnects relay 261 of repeater OR1 from release trunk conductor 282 of the trunk incoming to that repeater, and connects the ground to the release trunk conductor to mark the repeater busy.

The loop circuit extended by the repeater IR includes line relay 301 of selector S as follows: battery, upper winding of relay 301, armature 358 of relay 305, trunk conductor 250, armature 248 of relay 236 in repeater IR, upper right hand winding of repeating coil R1, upper winding of polarized relay 235, resistance 254, lower right hand winding of repeating coil R1, trunk conductor 251, 5 armature 361 of relay 305 in selector S, lower winding of relay 301 to ground. Relay 301 operates over the above-traced circuit and at armature 351 closes an obvious circuit for relay 302. Relay 302 operates and closes 10 the usual impulsing circuit.

Thus the subscriber at substation A upon dialling the two digits "0" and "1" is connected with incoming selector S in Y office through repeaters OR and IR. The subscriber's loop controls relay 202 of the repeater OR. Relay 202 controls the loop over which relay 236 of repeater IR operates. The two loops are inductively connected by repeating coil R. Relay 236 controls the 25 loop over which relay 301 of selector S operates. This loop is inductively connected with the loop between repeaters OR and IR by repeating coil R1.

It will now be assumed that the third digit 30 dialled by the calling subscriber is the digit "0". Relay 202 of repeater OR responds to each interruption of the calling loop, deenergizing and reenergizing ten times. With each deenergization of relay 202, the loop 35 circuit to relay 236 of repeater IR is opened and relay 236 deenergizes and reenergizes in response. Each deenergization of relay 236 opens the loop circuit of relay 301 of selector S, relay 301 deenergizing and reenergizing 40 in response to the interruptions. The impulses from the calling device are thus repeated to the incoming selector in the distant office.

Selector S is of the ordinary Strowger 45 type whose operation is well known in the art. It is therefore thought unnecessary to describe its operation in detail. Relay 301 responds to the dialled impulses and the vertical magnet operates to step the wipers to 50 the tenth level. Relay 304 and the rotary magnet then cooperate to step the wipers onto the bank contacts and hunt for an idle trunk in the usual manner. When an idle trunk is found, for example the trunk comprising conductors 329 to 332, inclusive, relay 305 operates, disconnecting line relay 301 from the control loop and switching the loop 55 through the succeeding switch.

The loop from the repeater IR is thereby 60 extended to the line relay 404 of repeater OR2, circuits of which may be traced as follows: battery, upper winding of relay 404, contacts controlled by armature 416 of relay 405, upper left hand winding of repeating coil R3, trunk conductor 329, bank contact 65

321, wiper 311 of selector S, armature 358 of relay 305, trunk conductor 250, thence through the loop in repeater IR over which relay 301 previously operated, trunk conductor 251, armature 361 of relay 305, wiper 312, bank contact 322, trunk conductor 330, lower left hand winding of repeating coil R3, contacts controlled by armature 417 of relay 405, through the lower winding of relay 404 to ground. Release trunk conductor 252 upon which ground is placed by relay 231 of repeater IR is extended by way of armature 360 of relay 305, wiper 313, bank contact 323, trunk conductor 331, normally closed contact and armature 457 of relay 453 through the winding of relay 407 to battery. Metering conductor 253 is extended by way of armature 359, wiper 314, bank contact 324, trunk conductor 332 to contacts at armature 418 of relay 405.

Relay 407 operates over the above traced circuit and at armatures 425 and 427 switches trunk conductors 428 and 429 from repeater IR1 to the talking conductors of repeater OR2. Relay 404 operates over the previously traced loop circuit and at armature 412 connects the upper winding of relay 402 to trunk conductor 428 by way of the upper right hand winding repeating coil R3 and armature 425 of relay 407. At armature 413 an obvious circuit is closed for relay 406. Relay 406 operates and at armature 421 closes a point in the circuit of relay 405, at armature 422 connects an additional ground to release trunk conductor 331, at armature 423 connects ground to trunk conductor 429 by way of lower right hand winding of repeating coil R3 and armature 427 of relay 407, and at armature 424 closes a point in the circuit of relay 401.

The loop circuit is thus extended to repeater IR2 including lower winding of relay 503, contacts controlled by armature 513 of relay 502, left hand windings of repeating coil R5, armatures 511 and 512 of relay 501, trunk conductors 428 and 429, armatures 425 and 427 of relay 407, right hand windings of repeating coil R3, to ground at armature 423 of relay 406, and to battery through the upper winding of relay 402. Relay 402 operates over the above-traced circuit and opens a point in the circuit of relay 405.

Line relay 503 of repeater IR2 energizes in series with relay 402 over the previously traced circuit and at armature 514 removes ground from the impulsing conductor of the repeater, and at armature 515 closes an obvious circuit for relay 504. Relay 504 operates and at armature 516 closes a point in the circuit of relay 506; at armature 517 closes a point in the circuit of relay 505; at armature 518 closes a circuit from ground through relay 507, conductor 510, off-normal contact 539 of selector S2, windings of relays 531 and 533 to battery. Relay 506 is not

operated at this time as no ground is present on the impulsive conductor of the trunk. Relay 505 does not operate as the circuit is opened at armature 515 of relay 503. Relay 507, however, operates over the above-traced circuit and at armatures 524 and 525 connects trunk conductors 508 and 509 to the repeater. The visual signal 582 operates from ground on signal lead 581 to inform the operator that the trunk is being used.

Relays 531 and 533 of selector S operate in series with relay 507 in the circuit previously traced. Relay 531, upon operating at armature 540 connects impulsive relay 532 to trunk conductor 508, at armature 541 connects its own lower winding to trunk conductor 509, and at armature 542 opens a point in the circuit of the release magnet and closes a point in the vertical impulsive circuit. Relay 533 upon operating at armature 545 connects relay 534 to test wiper 554, at armature 546 connects its own lower winding and upper winding in series with resistance 536 to control conductor 510, and at armature 547 closes a point in the rotary circuit.

Incoming selector S₂ is now ready to receive the calling subscriber's fourth digit. Assuming that the digit nine is now dialed, the interruptions of the calling loop will be repeated by repeaters OR and IR as previously described to relay 404 of repeater OR₂. Relay 404 deenergizes and reenergizes in response to the repeated impulses. With each deenergization of relay 404, the previously traced loop circuit of relay 503 is opened at the armature 412 of relay 404. With each deenergization of relay 404 a circuit is closed for relay 401 at armature 413, this circuit also includes armature 424 of relay 406. Relay 401 operates on the first deenergization of relay 404 and remains energized during the series of impulses due to its slow release character. Relay 401 closes a holding circuit for the lower winding of relay 402 at armature 408. Relay 402 therefore remains energized when its initial energizing circuit is interrupted at the contacts of relay 404. Shortly after the last impulse of the series, relay 401 deenergizes and opens the holding circuit of relay 402 which is now energized over the loop.

As relay 404 opens its upper contacts in response to the dialed impulses, the circuit of relay 503 of repeater IR₂ will be opened a like number of times and relay 503 will respond. With each deenergization of relay 503, a circuit will be closed from ground, armature 514 of relay 503, upper right hand winding of repeating coil R5, armature 524 of relay 507, trunk conductor 508 to selector S₂, armature 540 of relay 531, winding of relay 532 to battery. A circuit for relay 505 is also closed from grounded armature 515 of relay 503 and armature 517 of relay 504. Relay 505 operates on the first impulse

and remains operated throughout the series of impulses due to its slow release construction. Relay 504 is also slow to release and remains operated when its circuit is momentarily opened during impulsive. Relay 505 on operating at armature 520 opens a point in the circuit of relay 506, and at armature 522 connects battery through resistance 521 to trunk conductor 509.

Relay 532 of selector S₂ operates over the above-traced circuit in response to the repeated impulses and closes the circuit of the vertical magnet a like number of times. The vertical magnet operates and steps the switch shaft and wipers up to the called level. The off-normal springs 539 and 557 operate on the first vertical step of the shaft opening the initial energizing circuit of relays 531 and 533. Relay 533 remains energized over the previously traced locking circuit including its upper and lower windings and resistance 536 in series. Relay 531 remains operated during the series of impulses, its lower winding being energized from battery on trunk conductor 509.

Shortly after the last impulse of the series, relay 505 of repeater IR₂ deenergizes and opens the holding circuit of relay 531 which also deenergizes. Relay 531 on deenergizing closes the usual rotary stepping circuit and selector S₂ searches for an idle trunk in the usual manner.

On reaching an idle trunk which will be assumed to be that comprising conductors 561 to 563, inclusive, terminating on contacts 558 to 560, inclusive, relay 534 will operate over a circuit including relays in the succeeding switch corresponding to relays 531 and 533 of selector S₂. Relay 534 on operating at armatures 548 and 549 switches trunk conductors 508 and 509 through to conductors 561 and 562 by way of wipers 552 and 553 and contacts 558 and 559.

The trunk comprising conductors 561 to 563, inclusive, extends to a regular selector S₅ of the local switch train of office Z. This train may include one or more ranks of selectors and a rank of connectors. As the remainder of the digits are dialed by the calling subscriber, relay 503 of repeater IR₂ responds and repeats the impulses to the succeeding switches in the same manner as described for selector S₂. Selector S₂ cannot operate from these impulses since impulsive relay 532 is disconnected from the trunk at armature 540 of relay 531 and the energizing circuit of relay 531 is open at the operated off-normal springs.

The remaining digits operate the intermediate selectors and the connector in a manner well known in the art to connect with the wanted line such as A4. If the line is busy, a busy tone will be returned by the connector to inform the calling party that the wanted line is not available whereon the

calling subscriber will replace the receiver. If the wanted line is idle, the connector will signal the called station in the usual manner and return a ring-back tone to the calling subscriber.

When the called subscriber answers, the ringing current is cut-off in the usual manner and the connector places a ground on the upper trunk conductor. This ground extending back through the local switch train over conductor 561, contact 558, wiper 552, armature 548 of relays 534 in selector S₂, conductor 508, armature 524 of relay 507 in repeater IR₂, armature 516 of relay 504, armature 520 of relay 505, resistance 523 to relay 506. Relay 506 operates and at armature 526 closes a circuit for relay 502 including armature 518 of relay 504. Relay 502 operates and at contacts controlled by armature 513, disconnects the lower winding of relay 503 from the control loop and connects the upper and lower windings in series across the loop.

As previously described, relay 402 energized over the control loop in series with the lower winding of relay 503. When both windings of relay 503 are connected in the circuit, the current flow in relay 402 is reduced and relay 402 deenergizes. Relay 402 on deenergizing closes a circuit for relay 405 at armature 409 and the armature 421 of relay 406. Relay 405 operates and at contacts controlled by armatures 416 and 417 reverses battery over the loop from repeater IR by means of the usual reversing circuit. Relay 405 at armature 414 closes a locking circuit for itself; at armature 415 closes a point in the circuit of relay 403 which has no function at this time; at armature 418 connects metering conductor 332 which extends back through selector S to metering conductor 253, to a contact in the left hand bank of rotary switch RS through resistance 436; at armature 419 removes ground from the right hand bank contacts of rotary switch RS; and at armature 420 connects a lead from the interrupter to the rotary magnet of rotary switch RS. Interrupter INT is adjusted to send out ground impulses at predetermined intervals. Each impulse causes the rotary magnet 434 to energize. When the rotary magnet deenergizes after each impulse, wipers 430 and 431 are advanced one step in a counter clock-wise direction. On the first rotary step, battery is connected to a meter lead 332 by way of wiper 430, contact 432, resistance 436, and armature 418 of relay 405. The rotary switch continues to step as long as relay 405 is energized and at each twenty-fifth step, closes the above-traced circuit for the meter lead. It is obvious that the interval between metering impulses can be varied by adjusting the speed of the interrupter or by attaching the metering conductor to other bank contacts.

As previously mentioned, relay 405 re-

verses the direction of current flow in the control loop. The loop as previously described, includes the upper winding of polarized relay 235 in repeater IR. The two windings of relay 235 now assist each other and the relay operates and closes an obvious circuit for relay 234. Relay 234 on operating at armature 244 connects relay 233 to metering conductor 253; at contacts controlled by armatures 245 and 246 reverses the trunk conductors 207 and 208 with relation to relay 236, at the same time connecting the upper winding of relay 232 in series with the upper winding of relay 236. Relay 232 operates and at armature 240 disconnects its upper winding from the previously mentioned series circuit and connects the upper winding of relay 236 directly to the loop circuit; at armature 241 closes a locking circuit for its lower winding to ground in the release trunk; and at contacts controlled by armature 242 disconnects the lower winding of relay 236 from the trunk and closes a short circuit around condenser 237 including armature 245 of relay 234. The trunk circuit has now been changed from the loop type to the simplex type. The upper winding of relay 236 is now connected with both conductors of the trunk by way of armature 240 of relay 232, contacts controlled by armature 243 of relay 233, contacts controlled by armature 246 of relay 234, and the short circuit around condenser 237 previously closed by relay 232. Relay 236 remains operated over a circuit which will be described hereinafter.

Relay 233 is connected to meter lead 220 and operates with each metering impulse transmitted over the lead from repeater OR₂. Relay 233 on operating, at contacts controlled by armature 243, disconnects the upper winding of relay 236 from the trunk conductors and connects it to a holding ground. The simplex trunk is therefore cut "dry" with each metering impulse, that is, battery through the upper winding of relay 236 is disconnected.

Current flow was reversed in the control loop extending from repeater OR by the operation of relay 234 in repeater IR. The reversal of current flow in the loop which includes the upper winding of relay 201, causes the two windings of this relay to assist each other and the relay operates. Relay 201 on operating short circuits condenser 209 at armatures 210 and 214. A branch of the short circuiting lead extends through the lower winding of relay 203 to ground. Ground through relay 203 is thus connected to both sides of the trunk and serves to maintain relay 203 and also relay 236 of repeater IR energized over a simplex circuit including both trunk conductors. Relay 201 at armature 211 also opens the initial energizing winding of relay 203, and closes a locking circuit for its own lower winding by

short circuiting resistance 206; at contacts controlled by armatures 212 and 213 reverses the current flow over trunk conductors 167 and 168 in the usual manner; and at armature 215 closes a point in the metering circuit including conductor 170.

As previously described, metering impulses transmitted from repeater OR₂ cause the periodic operation of relay 233 of repeater IR which on operating cuts the simplex trunk dry by disconnecting battery which is fed to the trunk through the upper winding of relay 236. Each time battery is disconnected from the trunk, relay 203 of repeater OR will deenergize and connect battery through resistance 222 to metering conductor 170 at armature 218. Metering conductor 170 extends back through contact 162, wiper 118 of connector C, armature 124 of relay 101, conductor 21, wiper 10 of the calling line switch LS, armature 12 of relay 3, to the subscriber's meter 6. The meter will operate in response to each metering impulse repeated by repeater OR to register the charge for the completed call.

If the connection is maintained longer than the unit charging interval, the second revolution of the wipers of rotary switch RS associated with repeater OR₂ will cause the meter to register again. Thus at regular pre-determined intervals during the course of the connection, the meter will be operated to register the charge on the basis of duration of the call.

At the termination of the conversation both subscribers will restore their receivers. If the called subscriber hangs up first, nothing happens, as the connector is ordinarily arranged for release by the last party. The connector, however, maintains the ground on the upper trunk conductor so that the calling subscriber's meter will continue to register until the receiver is restored.

When the calling subscriber restores the receiver at substation A, the calling loop will be opened at the switch hook springs in the usual manner. Relay 202 of repeater OR which was energized over the loop will retract its armatures, opening the simplex circuit to repeater IR in the distant office, and opening the circuit of relay 204. Relay 204 restores, removes ground from the release trunk conductor 169, opens the holding circuit of relay 201, and opens a point in the simplex circuit to the switch ahead. Relay 205 deenergizes as soon as ground is removed from the release trunk and switches the trunk conductors 207 and 208 back to incoming connector C₁. Relay 201 restores and re-connects line relay 202 to the trunk conductors in the normal manner. Relay 203 restores when the second point in the simplex circuit is opened by relay 204. The repeater is now in normal condition.

The removal of ground from the release

trunk as above described causes relays 111 and 101 of connector C, and relay 3 of line switch LS to deenergize. Relay 111 on restoring disconnects the line wipers from the talking conductors, connects test wiper 117 in the normal testing circuit and closes a point in the circuit of the rotary magnet. Relay 101 on restoring switches the trunk conductors back to line relay 103, opens a point in the metering circuit, and closes a circuit for the release magnet including armature 129 of relay 103, armature 131 of relay 104, and operated off-normal spring contacts 120. Release relay 114 energizes and permits the switch shaft and wipers to restore to normal in the usual manner. The shaft on reaching its normal position opens the circuit of the release magnet at the off-normal springs, and closes a part of the normal energizing circuit of relays 104 and 105.

Relay 3 of the line switch LS restores and reconnects the line conductors to line relay 4 and ground respectively. The wipers remain on the contacts of the trunk just used.

When the control loop is opened in repeater OR, relay 236 of repeater IR deenergizes. If relay 233 is energized in response to a meter impulse at this moment, the de-energization will take place as soon as relay 233 restores. Relay 236 opens the loop circuit to the succeeding switch and also opens the circuit of relay 231. Relay 231 deenergizes and removes ground from the release trunk conductor 239 and also disconnects release trunk conductor 282 of repeater OR₁ from ground and connects it to relay 261. The busy condition being removed, repeater OR₁ can now be seized for another call. Ground being removed from the release trunk, relays 232 and 235 deenergize. Relay 232 on restoring changes the simplex holding circuit back to a loop circuit and opens its own holding winding. Relay 235 on deenergizing opens the circuit of relay 234 which restores and connects relay 236 to the trunk conductors in the normal manner.

The removal of ground from release trunk conductor permits the restoration of relay 305 of selector S. Relay 305 closes the usual circuit for the release magnet which causes the switch shaft and wipers to return to normal in the usual manner. The release magnet circuit is opened at the off-normal springs which open when the shaft reaches its normal position.

The holding loop for relay 404 of repeater OR₂ being opened at repeater IR, this relay deenergizes. Relay 404 opens a part of the loop circuit to the switch ahead and opens the circuit of relay 406. Relay 406 deenergizes and opens the circuit of relays 401, which operated momentarily when relay 404 deenergized; opens the holding circuit of relay 405 and removes the additional holding

ground from the release trunk to the preceding switch.

Relay 402 deenergizes immediately after the release of relay 401, its initial energizing circuit being open at contacts of relay 404 which has deenergized. Relay 407 deenergizes as soon as ground is removed from the release trunk and switches the trunk conductors back to incoming repeater IR1. Relay 405 deenergizes and opens a point in its own holding circuit, opens a part of the circuit of relay 403, disconnects metering conductor 332 from pulsing mechanism M, connects a ground to the right hand bank contacts of rotary switch RS, and disconnects the interrupter lead from the rotary magnet. If the wipers of rotary switch RS are in their home position no action takes place; however, if the wipers are in any other position a circuit for the rotary magnet will be closed including armature 419 and normally closed contact of relay 405, right hand bank contact of switch RS, wiper 431, and rotary interrupter springs 435. The rotary magnet energizes, opens its own circuit at the interrupter springs, and in deenergizing steps the wipers ahead. This operation is repeated as long as wiper 431 encounters a grounded contact. When the home contact is reached, no ground being found thereon, the stepping operation ceases. All relays of repeater OR₂ having restored, the switch is now in normal condition.

The loop circuit for relay 503 being opened at repeater OR₂, the relay deenergizes and opens the circuit of relay 504, and closes a circuit for relay 505. Relay 504 deenergizes, opens a point in the circuit of relay 506, opens the circuit of relay 505, disconnects signalling lead 581 from ground and connects it to cut-off relay 501, and removes ground from relay 507 and control lead 510 to the selector. Relay 505 deenergizes, the momentary energization when relay 503 restores has no utility. Relay 506 deenergizes and opens a point in the circuit of relay 502. Relay 502 deenergizes and again connects the lower winding of relay 503 to the trunk conductors. Relay 507 restores and disconnects trunk conductors 508 and 509 from the repeater.

In selector S₂, relay 533 deenergizes when ground is removed from control lead 510. Relay 533 disconnects relay 534 from control wiper 554 and closes a part of the release circuit. Relay 534 restores, disconnects wipers 552 and 553 from trunk conductors 508 and 509 and completes the circuit of the release magnet including operated contacts 557 of the off-normal springs. The release magnet energizes, the shaft and wipers return to the normal position in the usual way, and the circuit of the release magnet is again opened at the off-normal springs.

The local switch train following selector S₂ releases in the well known manner.

It will now be assumed that the subscriber at substation A in X office desires a connection with a subscriber in a nearby town to which a suburban service is maintained. The calling subscriber dials the digits required for reaching selector S₂ as described in the preceding connection and is connected with selector S₂. Assuming that the subscriber now dials the digit "0", selector S₂ operates as described before and selects an idle trunk on the tenth level, for example the trunk comprising conductors 564 to 566, inclusive, terminating on contacts 555 to 557, inclusive, leading to operator's position OA.

It will be recalled that selector S₂ extended a ground through relay 534 over control wiper 554. This ground extends by way of contact 560, conductor 557, through the short circuit around the upper winding of relay 572 including armatures 573 and 575 of relays 571 and 572, respectively, through the lower winding of relay 572 to battery. Relay 572 energizes and opens the short circuit around its upper winding. Relay 572 remains energized over both windings in series, and at armature 576 closes a circuit for the supervisory lamp including armature 574 of relay 571. The supervisory lamp now burns to inform the operator that a call has been extended.

To answer the call, the operator inserts the answering plug of a regular cord in the answering jack and establishes a talking connection with the calling party in the usual way. The insertion of the plug into the jack also closes an obvious circuit for relay 571 which operates, opens another point in the short circuit around the upper winding of relay 572 and opens the circuit of the supervisory lamp. The supervisory lamp is now extinguished at all positions in which the trunk is multipled, indicating that the call has been answered.

The operator determines the number of the wanted subscriber and extends the call by means of the other plug of the answering cord. When the called subscriber answers, the operator is so informed by the usual supervisory signals in the cord. The operator then momentarily depresses the meter key, which connects ground to trunk conductor 564 at contact 577. Relay 506 of repeater IR₂ operates from this ground in the same manner as when the connector placed a ground on the upper trunk conductor. Relay 502 operates and connects both windings of relay 503 in series in the control loop whereon relay 402 of repeater OR₂ deenergizes as previously described. The operation of relay 405 and metering device M takes place in the same manner as on a call to a subscriber in Z office.

The operator then releases the meter key which removes the ground from conductor 564 whereon relays 506 and 502 of repeater IR₂ restore. The lower winding only of relay

503 is now connected in the control loop and relay 402 again attracts its armatures. Relay 405, however, remains locked up through its upper armature. Relay 402 on energizing 5 closes a circuit for relay 403 including armature 415 of relay 405 and the upper armature 409 of relay 402. Relay 403 operates and at its upper armature closes a locking circuit for itself independent of the contacts 10 of relays 402 and 405. Relay 403 at armature 411 connects another contact of the left hand bank of rotary switch RS to the meter lead 332. With each revolution of the wipers, two metering impulses will be transmitted 15 as wiper 430 passes over contacts 432 and 433 of the bank. The metering impulses are repeated back to the calling subscriber's meter in the same manner as previously described for calls to Z office subscribers.

20 At the termination of the call, the operator receives the usual cord supervision when either party hangs up. The operator then removes the plug from the answering jack and the switches restore to normal as previously described.

The operations involved in setting up a call from the subscriber at substation A (Fig. 1) in X office to the subscriber at substation A₃ (Fig. 7) in Y office will now be considered. The subscriber at substation A lifts the receiver and dials the digits "0" and "1" which operate connector C and extend the calling loop through repeaters OR and IR to selector S exactly as described for a call to 35 Z office. The third digit operates selector S which selects an idle trunk as previously described. It will be assumed that the third digit dialled was "9" and that the wipers of selector S stop on contacts 325 to 328 associated with the trunk comprising conductors 40 325 to 328, inclusive, terminating in connector C₂ (Fig. 7).

Connector C₂ is an ordinary Strowger type connector, the operation of which is well known in the art. It is therefore thought unnecessary to describe its operation in detail. When selector S switches through, the control loop from repeater IR is extended to line relay 702 of connector C₂. Line relay 50 702 and release relay 703 operate in the usual manner. The subscriber then dials the last two digits of the called number, the interruptions of the loop being repeated by repeaters OR and IR as previously described. Line relay 702 of connector C₂ operates in response to the repeated impulses and completes the usual vertical and rotary stepping circuits. The wipers 735, 736 and 737 of the connector will be advanced to the contacts of the called line which will be assumed to be contacts 738, 739 and 740 associated with conductors 741, 742 and 743 terminating in line switch LS_s.

If the called line is busy, test wiper 737 65 will encounter a ground on contact 740 and

test relay 706 of the connector will operate in the usual way to return a busy tone to the calling subscriber. If the called line is idle, cut-in relay 708 of the connector and cut-off relay 752 of the line switch will operate in 70 the usual manner and ringing current will be applied automatically to the called line. Relay 752 is prevented from operating its full stroke by a mechanical locking device which permits the back contacts to open but 75 prevents the front contacts from closing. This cuts off the normal battery and ground connections from the line but does not close through a circuit to the wipers.

When the called subscriber lifts the receiver at substation A₃, a direct current circuit is closed for the upper winding of ring-cut-off relay 705 of the connector. Relay 705 operates and in the usual manner cuts off the ringing current and connects the talking conductors through to the back-bridge relay 701. Relay 701 feeds battery and ground to the called line and operates over the called subscriber's loop. Relay 701 on operating reverses the trunk conductors with relation to line relay 702 which reverses the direction of the current flow in the control loop. Relay 235 of repeater IR operates when the current flow is reversed in the control loop, and changes the control loop between repeaters 90 OR and IR to a simplex holding circuit as described under calls to Z office. As in the previously described connection, relay 236 through its upper winding and relay 203 through its lower winding are energized in 95 series over the simplex circuit.

When relay 705 of the connector operates it also connects battery to metering conductor 344 through resistance 709. Relay 233 of repeater IR operates from this battery, closes a 100 holding circuit for relay 236 and cuts off the battery from the simplex circuit. Relay 203 of repeater OR deenergizes and closes the metering circuit as previously described which causes the meter associated with line switch 105 LS to operate.

During the conversation the voice currents will be transmitted over the dry simplex circuit to repeating coil R by which the simplex circuit is inductively connected to the 110 calling subscriber's loop. At the end of the conversation, both subscribers will restore their receivers and the switches will release in the manner previously described. It is obvious from the foregoing description that 115 the calling subscriber's meter will register only once on calls from X to Y office.

The connections dealt with up to this time have involved trunking between two or more offices. The operations involved in a call 120 from substation A to substation A₁, both in X office will now be considered.

When the subscriber at substation A lifts the receiver, line switch LS operates as previously described and selects an idle trunk 125

which will be assumed to be the trunk terminating in connector C. Connector C responds to the first digit in the same manner as described under trunk calls and steps the 5 wipers to the called level. It will be assumed that the digit "9" is dialled and that the wipers are raised to the ninth level. The operations so far have been exactly the same as for trunk calls except that the shaft springs are 10 not operated when the shaft and wipers reach the ninth level. The connector now responds to the second digit which will be assumed to be a "5" and the wipers are rotated into engagement with contacts associated with line 15 95. This line for example may be the one comprising conductors 171, 172 and 173 terminating on contacts 163, 164, and 165 and leading to line switch LS', associated with substation A₁. Contact 166 of the banks is multipled with contact 165 on individual lines.

If substation A is busy, test wiper 117 will encounter a ground on contact 165. Referring to the first connection described, it will be understood that relays 109 and 110 of connector C are operated during the rotary impulsing. Relay 108 which is connected to the test wiper by way of contacts controlled by armature 149 of relay 110 operates from the ground encountered by the test wiper. As 20 contacts 165 and 166 are strapped together, wiper 118 will also encounter a ground. Shortly after the last rotary impulse relay 109 deenergizes and at armature 145 closes a circuit for the lower winding of relay 110 to 25 ground on wiper 118. As previously explained, the two windings of relay 110 oppose each other and the relay deenergizes. Relay 109 on deenergizing also closes a point in the circuit of relay 107 but this relay does 30 not energize since its circuit is also opened at armature 152 of relay 110 which is now deenergized. Relay 108 on operating closed a point in its own locking circuit, closed a point in the circuit of the upper winding of relay 35 110, opened the rotary impulsing circuit, and closed a point in the busy tone circuit. Relay 110 on deenergizing opened the circuits to both its upper and lower windings, disconnected the test wiper from relay 108 and 40 closed a point in the locking circuit of that relay, removed the shunt around the armature 143 of relay 108, opened a point in the circuit of relay 107 and closed a point in the busy tone circuit. Busy tone is now applied to the 45 lower talking conductor to inform the calling subscriber that the called line is not available at this time. The calling subscriber then restores the receiver and connector C and line switch LS return to normal as previously described.

In case the called line is idle, the test wiper will find battery potential on the test contact and relay 108 will not energize. When relay 109 falls back shortly after the last 50 rotary impulse, the circuit of the upper

winding of relay 110 will be opened. Relay 110 on deenergizing switches the test wiper from relay 108 to the lower winding of relay 111. A circuit is thus closed from ground on the release trunk, contacts controlled by armature 155 of relay 111, armature 141 of relay 108, lower winding of relay 111, armature 149 of relay 110, test wiper 117, test contact 165, conductor 173, winding of relay 3' of line switch LS₁, interrupter springs 17', winding of magnet 5' to battery. Relay 111 operates over the above traced circuit and at armatures 154 and 158 connects the line wipers to the ringing equipment; at contacts controlled by armature 155 opens a part of the circuit of its own lower winding and connects test wiper 117 to the grounded release trunk; at armature 156 closes a locking circuit for its own upper winding; and at armature 157 opens the circuit of the 55 rotary magnet.

Relay 3' of line switch LS₁ energizes in series with relay 111 and moves its armatures far enough to open the back contacts but not enough to close the front contacts. The complete stroke of the armatures is prevented by a mechanical locking device controlled by line relay 4' and is well known in the art. The partial operation of relay 3' disconnects the normal battery and ground connections from the called line.

Ringing current is now automatically sent over the line at intervals controlled by the ring interrupter to operate the bells at substation A₁. It will be noted that the ringing circuit includes the lower winding of relay 106, and that during the silent period a ground is connected to the lower trunk conductor. When the called subscriber at substation A₁ answers by lifting the receiver, a direct current path is closed over which relay 106 energizes. Relay 106 on energizing, at armatures 135 and 138 opens the ringing circuit and switches the called line loop through to back bridge relay 102; at armature 136 100 connects battery to metering conductor 21; and at armature 137 closes a locking circuit for its own upper winding. Relay 102 feeds talking battery to the called subscriber and operates over the called subscriber's loop. Relay 102 on operating reverses the trunk conductors with respect to line relay 103 by means of the usual reversing circuit. The reversal of battery has no utility in this connection. The meter associated with the 105 calling line switch LS energizes from the battery on the metering conductor.

At the termination of the conversation, both subscribers replace their receivers and the switches release as previously described. 110 The meter associated with line switch LS remains energized throughout the connection and consequently registers only once for the call.

A call from the operator Z office to a sub- 115

scriber at substation A will now be described. The operator observing that the trunk circuit OC is idle, inserts the calling plug of a cord into the call jack. An obvious circuit 5 is closed for relay 501 which operates and switches trunk conductors 428 and 429 from repeater IR_2 to calling circuit OC. Visual signal 582 also operates to indicate that the trunk is now busy. A loop circuit is closed 10 including the upper winding of relay 451 of repeater IR_1 and the lower winding of relay 591 of calling circuit OC as follows: battery, lower winding of relay 591, normally closed contact 587 of the dial key, upper 15 left hand winding of repeating coil R_6 , armature 511 of relay 501, trunk conductor 428, armature 425 of relay 407 in repeater OR_2 , upper right hand winding of repeating coil R_4 associated with repeater IR_1 , upper 20 winding of relay 451, normally closed contacts controlled by armature 456 of relay 452, lower right hand winding of repeating coil R_4 , armature 427 of relay 407, trunk conductor 429, armature 512 of relay 501, 25 lower left hand winding of repeating coil R_6 to ground. Relays 591 and 451 operate over the above circuit. Relay 591 on operating opens the short circuit around condenser 584 and this opens the loop through 30 the operator's cord circuit extinguishing the supervisory lamp (not shown). Relay 451 on operating closes an obvious circuit for relay 453 and also closes a part of the loop circuit to the line relay of incoming selector 35 S_1 . Relay 453 on operating at armature 457 opens the circuit of relay 407 and grounds the release trunk of repeater OR_2 to mark that repeater busy; at armature 458 completes the loop circuit to selector S_1 including 40 the upper winding of polarized relay 452 and impedance coil 454; and at armature 459 closes a circuit for the lower winding of relay 452. Relay 452 does not operate at this time as its two windings oppose each other. 45 Selector S_1 is exactly the same as selector S previously described and, therefore, its operation will not be described in detail. The line relay energizes over the loop extended by repeater IR_1 . The selector is now 50 ready to receive the first digit.

In order to dial, the operator presses the dial key which is a locking key. At contacts 586 and 587 the battery feed to the control loop is transferred from the lower winding of relay 591 to resistance 583 through the impulsing contacts of the calling device or dial. A locking circuit for the upper winding of relay 591 is closed at contacts 585 to keep this relay energized during the dialing so that normal supervision will be given in the cord circuit. The operator then dials the first digit. Assuming the first digit to be an "0", the control loop is momentarily opened ten times. Relay 451 of repeater IR_1 responds to the interruptions and at

armature 458 interrupts the loop to selector S_1 a like number of times. The line relay of selector S_1 responds to the loop interruptions in the usual way and the wipers of the selector are advanced to the tenth level. The switch then cuts in and rotates the wipers into engagement with the contacts of an idle trunk, for example contacts 471 to 474, inclusive, associated with the trunk comprising conductors 280 to 283, inclusive, terminating in outgoing repeater OR_1 . 70

The control loop is thus extended from repeater IR_1 , through selector S_1 by way of wipers 461 and 462, contacts 471 and 472, trunk conductors 280 and 281, right hand windings of repeating coil R_2 of repeater OR_1 , normally closed contacts controlled by armatures 271 and 272 of relay 263, through the upper and lower windings of relay 264 to battery and ground respectively. The release trunk is extended from the selector by way of wiper 464, contact 474, conductor 282, armature 239 of relay 231 of repeater IR , to relay 261 of repeater OR_1 . Relay 261 operates and switches trunk conductors 207 and 208 from repeater IR to repeater OR_1 . The metering conductor is also extended from selector S_1 by way of wiper 463, contact 473, and conductor 283 to repeater OR_1 but has no utility in this connection. Relay 264 operates over the loop extended from repeater IR_1 , closes an obvious circuit for relay 265 and completes a loop circuit to the line relay of incoming connector C_1 , including trunk conductors 207 and 208, armatures 268 and 269 of relay 261, armature 274 of relay 264, left hand windings of repeating coil R_2 , resistance 267 and upper winding of polarized relay 262. Relay 265 operates and places ground on the release trunk to hold up selector S_1 and to maintain relay 261 energized, and closes a circuit for the lower winding of relay 262. Relay 262 does not operate at this time as the two windings oppose each other. 95

Connector C_1 is exactly the same as connector C and it is therefore unnecessary to explain its operation in detail. The line relay, corresponding to relay 103 of connector C , energizes over the loop extended from repeater OR_1 and closes the circuit of relay 104' which corresponds to release relay 104 of connector C . Relay 104' grounds the release trunk of connector C to mark that switch busy and opens the circuit of cut-off relay 205. The second and third digits are now dialled by the operator. The loop interruptions are repeated by relay 451 of repeater IR_1 to relay 264 of repeater OR_1 which in turn repeats the interruptions to the line relay of connector C_1 . The line relay of the connector responds in the usual manner and wipers 115', 116' and 117' are advanced to the contacts of the called line which will be assumed to be contacts 163', 164' and 165' as 100 105 110 115 120 125 130

sociated with the trunk comprising conductors 171, 172 and 173 terminating in line switch LS_1 . The operation of connector C_1 and line switch LS_1 are exactly the same as 5 described for connector C and the line switch on local calls in X office.

If the called line is busy, the connector places a busy tone on the line to inform the calling operator that the called line is engaged. If the called line is not busy, ringing current is sent out by the connector as previously described.

When the called subscriber answers, the back bridge relay corresponding to relay 102 15 of connector C operates and reverses trunk conductors 207 and 208 with respect to the line relay of connector C_1 . The current flow through the upper winding of relay 262 of repeater OR_1 is reversed and the two windings now assist each other. Relay 262 energizes and closes a circuit to relay 263 which 20 also energizes and by means of the usual reversing contacts, reverses trunk conductors 280 and 281 with respect to relay 264. Relay 263 also closes a circuit for the lower winding of relay 266. Relay 266 operates and 25 locks itself in parallel with the lower winding of relay 262 to ground at the lower armature of relay 265. Relay 266 also connects its upper winding to metering conductor 283 but this operation has no utility in this connection.

With the reversal of conductors 280 and 281, the current flow in the upper winding 35 of relay 452 of repeater IR_1 is such that the two windings of this relay assist each other and the relay operates. Relay 452 connects both windings of relay 451 in series in the control loop from operator's circuit OC.

40 After dialling the last digit the operator restores the dial key to normal and transfers the energizing circuit of relay 591 back to the control loop. Relay 591 remains energized in series with the upper winding of relay 451 45 of repeater IR_1 . When the two windings of relay 451 are connected in series in the control loop, relay 591 deenergizes due to the high resistance of these two windings which 50 reduce the current flow in the control loop. Relay 591 on deenergizing closes a short circuit around condenser 584 to operate the usual answering supervisory circuits in the calling cord and to complete the talking circuit for the calling line.

55 When the called subscriber replaces the receiver at substation A_1 , the back bridge relay of connector C_1 deenergizes and reverses the trunk conductors back to normal. Polarized relay 262 of repeater OR_1 also restores and 60 reverses the trunk conductors back to normal. Polarized relay 452 of repeater IR_1 deenergizes and disconnects the lower winding of relay 451 from the loop circuit. Relay 591 of operator's circuit OC again operates in 65 series with the upper winding of relay 451 and

opens the short circuit around condenser 584 to give the operator the usual disconnect supervision.

The operator on receiving the disconnect signal withdraws the calling plug from the call jack opening the circuit of relay 501. Relay 501 deenergizes and switches the trunk conductors 428 and 429 from the operator's circuit OC to repeater IR_2 . Visual signal 582 restores to normal to indicate the idle condition of the trunk. Relay 451 of repeater IR_1 deenergizes when its operating loop is opened, and opens the loop to repeater OR_1 . Relay 451 also opens the circuit of relay 453 which retracts its armatures, removing the busying ground from the release trunk of repeater OR_2 and again connecting relay 407 thereto. Relay 453 also removes the ground from the lower winding of relay 452 which however had retracted its armatures when the called subscriber hung up. The loop circuit being opened, relay 264 of repeater OR_1 deenergizes, opens the loop circuit to connector C_1 and opens the circuit of relay 265. Relay 265 deenergizes and removes the holding ground from the release trunk allowing relay 261 to deenergize. Selector S_1 returns to normal in the usual manner when the holding ground is removed from the release trunk. Relay 265 also removes the ground from the lower windings of relays 262 and 266. Relay 266 deenergizes and disconnects its upper winding from metering conductor 283. Relay 262 had previously deenergized when the called subscriber hung up. Relay 261 on deenergizing switches trunk conductors 207 and 208 from repeater OR_1 back to repeater IR . The control loop being opened at repeater OR_1 , the line relay of connector C_1 deenergizes and the connector releases as previously described for connector C. Release relay 104' on restoring its armatures, disconnects the busying ground from the release trunk of repeater OR and connects cut-off relay 205 thereto. Relay 3' of line switch LS_1 deenergizes in the usual manner when the holding ground is removed from release trunk conductor 173 at connector C_1 .

In case the operator in Z office calls a subscriber such as A_3 in Y office, the following operations take place. The operator plugs in and dials the first digit exactly as described for a call to an X office subscriber. Instead of dialing the digit "0" however, let it be assumed that the digit "9" was dialed and that the selector S_1 advanced its wipers into engagement with contacts 475 to 478, inclusive. These contacts are associated with trunk conductors 341 to 344, inclusive, which terminate in connector C_2 (Fig. 7). Line relay 702 operates over the loop circuit extended by repeater IR_1 . The next two digits are repeated by repeater IR_1 as previously described and relay 702 responds. The wipers of connector C_2 are advanced to the con-

tacts of the called line exactly as described under calls from substation A to substation A₃. If the called line is busy, the connector returns the busy tone in the usual way to inform the operator that the called line is engaged. If the called line is idle, the connector cuts in and sends out ringing current in the usual manner. When the called subscriber answers, the ringing current is cut off and the back-bridge relay operates to reverse the battery over the trunk conductors in a manner well known. The reversal of battery permits polarized relay 452 of repeater IR₁ to operate and give the operator answering supervision in the same manner as described for calls to an X office subscriber. Disconnect supervision and release are the same as previously described.

The subscriber at substation A₂ in Y office may call the subscriber at substation A₁ in X office in the following manner: On lifting the receiver at substation A₂, the usual control loop is extended to line switch LS₂ which connects with an idle trunk in the same manner as line switch LS (Fig. 1) previously described. Assuming that the trunk selected is that comprising conductors 618 to 621, inclusive, the calling subscriber's loop is extended to selector S₄.

Selector S₄ is identical with selector S, the operation of which was previously described in detail. The selector responds to the first digit in the usual manner and advances the wipers 622 to 625, inclusive, into engagement with the contacts of an idle trunk, for example contacts 626 to 629, inclusive, associated with trunk conductors 280 to 283, inclusive, which terminate in repeater OR₁. The calling subscriber's loop is extended to repeater OR₁ which in turn extends a loop circuit to connector C₁. The second and third digits are repeated by repeater OR₁ and connector C₁ responds to advance its wipers to the contacts of the called line which is assumed to be substation A₁. The operation of repeater OR₁ and connector C₁ was previously described under calls from the Z office operator to substation A₁, and is the same in this instance.

If the called line is busy, the connector returns the usual busy signal to the calling subscriber. If the called line is idle, the connector sends out ringing current in the usual way to signal the called subscriber. When the called subscriber answers, the ringing current is cut off and connector C₁ and repeater OR₁ reverse battery over the calling trunk as previously described. It will be recalled that relay 266 operated when the connector reversed battery over the loop from repeater OR₁. Relay 266 on operating closes a locking circuit for its lower winding to ground on the armature 277 of relay 265. Relay 266 also closes a circuit which may be traced from battery, upper winding of relay

266, conductor 283, contact 629, wiper 625, through selector S₄, conductor 621, wiper 610 of line switch LS₂, armature 612 of relay 603, winding of meter 606 to ground. The meter operates over the above circuit and registers one completed call. Relay 266 being locked up will not release in case the called subscriber hangs up first. This prevents false registration of the meter in case the called subscriber again lifts the receiver before the calling subscriber releases the connection. When both subscribers hang up, the switches release in the usual manner.

To call a subscriber such as substation A₄ in Z office, the subscriber at substation A₂ removes the receiver and dials the first digit, operating line switch LS₂ and selector S₄ as previously described. Assuming that the digit "9" is dialled wipers 622 to 625, inclusive, of selector S₄ are advanced into engagement with the contacts of an idle line, for example contacts 630 to 633, inclusive, associated with conductors 329 to 332, inclusive, which terminate in repeater OR₂. The calling subscriber's loop is extended to repeater OR₂ which in turn extends a control loop to repeater IR₂. The subsequent digits are repeated by repeaters OR₂ and IR₂ and operate selector S₂ and the succeeding selectors and connector in Z office in the same manner as described for calls from substation A to Z office. When the called subscriber answers, the operations are also the same as in the previously mentioned connection. Relay 506 of repeater IR₂ operates from ground on the upper trunk conductor from connector C₃ in Z office. Relay 502 operates and connects the high resistance upper winding of relay 503 in the loop circuit from repeater OR₂. Relay 402 of repeater OR₂ deenergizes and relay 405 energizes. Metering mechanism M then connects battery to metering conductor 332 at predetermined intervals throughout the course of the connection, these impulses operating the meter associated with line switch LS₂ in the usual manner.

The connector in Z office maintains the ground on the upper trunk conductor even though the called subscriber hangs up. The meter of the calling station will therefore continue to register at the predetermined rate until the calling subscriber releases the connection. When both subscribers hang up, the switches return to normal in the usual manner.

Calls from substation A₂ to the operator at Z office are made in the same manner as calls to Z office subscribers except that the second digit "0" will operate selector S₂ to the tenth level where the selector will select an idle trunk to an operator's position, such as the trunk comprising conductors 564, 565 and 566 terminating in answering circuit OA.

The operator will extend the call as required, and if an additional charge is nec-

essary, will momentarily operate the meter key. Relay 402 of repeater OR₂ will deenergize momentarily and relays 404 and 405 will energize. Metering equipment M will then 5 send out two metering impulses for each revolution of the wipers of rotary switch RS in the same manner as on calls from substation A which was previously described in detail. The meter at substation A₂ will therefore 10 register double the normal amount during course of the call. When the calling party hangs up, the operator will receive the usual cord supervision whereupon the plug will be removed from the answering jack and the 15 switches will return to normal in the usual manner.

Local calls in Y office such as calls from substation A₂ to substation A₃ may be completed over switches, the operation of which 20 has previously been described in detail. These switches include line switch LS₂, selector S₄, connector C₂ and line switch LS₃. Metering is over the fourth trunk conductor and is effective when the called subscriber 25 answers.

Having described this invention, what is considered new and is desired to have protected by Letters Patent will be pointed out in the appended claims.

30 What is claimed is:

1. In a telephone system, a calling line and a meter associated therewith, a called line, an operator's position, means for extending a connection from said calling line 35 to either said called line or to said position, means responsive when a call is extended to said called line for operating said meter to register an impulse for each unit of time during the course of the call, and means responsive when a call is extended to said position and under the control of the operator for operating said meter to register a plurality of impulses for each unit of time during the course of the call.

45 2. In a telephone system, a calling line and a meter associated therewith, an operator's position, means for extending a connection from the line to said position, and means controlled by the operator for rendering said meter effective to automatically register a plurality of times at pre-determined intervals during the course of the call.

3. In a telephone system, a calling line and a meter associated therewith, a plurality 55 of called lines, means for extending a connection from said calling line to any one of said called lines, means effective when a connection is extended to certain of said called lines for operating said meter once for each completed call, and means effective when a connection is extended to other of said calling lines for operating said meter at pre-established intervals during the course of the call.

4. In a rotary connector for extending connections to called lines, a slow-acting relay

and a quick acting relay, means for operating said relays, means effective when a call is extended to an idle line for deenergizing said relays, a switching through circuit, and means responsive to the deenergization of 70 said relays for rendering said circuit effective.

5. In a switching connector for extending connections to subscriber's lines or to trunk lines, a metering conductor, means effective 75 when a call is extended to a subscriber's line for connecting a characteristic potential to said conductor, and means effective when a call is extended to a trunk line for connecting said conductor directly to a conductor of 80 the trunk line.

6. In a telephone system, a trunk line, means for extending a call over a loop circuit including two conductors of said trunk line in series, means for answering the call, 85 and means responsive when the call is answered for changing said loop circuit to a simplex holding circuit including the two conductors of said trunk in parallel.

7. In a telephone system, a repeater, a trunk line terminating in said repeater, means in the repeater for extending a call over a circuit including two conductors of said trunk line in series, means for reversing the direction of current flow over said loop circuit, a relay and means for operating it independent of any conductors of said trunk line, and means responsive to the reversal of current flow in said loop circuit for maintaining said relay operated over a circuit including the two conductors of said trunk in parallel.

8. In a telephone system, a repeater, a trunk terminating in said repeater, a relay, means for operating said relay over a circuit including two conductors of said trunk in series, and means for maintaining said relay energized over a circuit including the two conductors of said trunk in parallel.

9. In a telephone system, a repeater, an incoming trunk, an outgoing trunk, means for extending a call via said incoming trunk, said repeater, and said outgoing trunk, means for answering the call, means effective when the call is answered for altering the resistance of said outgoing trunk, and means in said repeater responsive to said resistance change for reversing the direction of current flow over the conductors of said incoming trunk.

10. In a telephone system, a repeater, an incoming trunk and an outgoing trunk, an operator's position, means for extending a call via said trunks and said repeater to said position, means in the repeater normally effective for connecting a characteristic potential to a conductor of said incoming trunk at certain pre-determined intervals, and means in the repeater controlled by the operator at said position whereby said second 120

means is rendered effective to operate at other pre-determined intervals.

11. In a telephone system, a repeater, a trunk comprising a plurality of conductors, 5 means for extending a connection via said trunk to said repeater, impulsing means in the repeater, means in the repeater for rendering said impulsing means effective to transmit an impulse over a conductor of said 10 trunk at pre-determined intervals, and means in said repeater for rendering said impulsing means effective to transmit a plurality of impulses over a conductor of said trunk at said pre-determined intervals.

15 12. In a telephone system, a trunk, a repeater, meter controlling means in said repeater, an operator's position, means for extending a connection via said trunk and said repeater to said position, means at said position controlled by the operator for momentarily applying a potential to a conductor of said trunk, and means in the repeater responsive to said application of potential for rendering said metering means effective.

25 13. In a telephone system, a line equipped with a meter, means for extending calls of three classes from said line, means responsive in a call of the first class for operating said meter to register one impulse independent of the duration of the call, means responsive in a call of the second class for operating said meter to register an impulse for each unit of time consumed by the call, and means responsive in calls of the third 30 class for operating said meter to register a plurality of impulses for each unit of time consumed by the call.

40 14. In a telephone system, a line equipped with a meter, means for extending calls of three classes from said line, means responsive in a call of the first class for operating said meter to register one impulse independent of the duration of the call, means responsive in a call of the second class for operating said meter to register an impulse for each unit of time during the course of the call, and means responsive in calls of the third class for operating said meter to register a plurality of impulses for each unit of time during the course of the call.

45 15. In a telephone system, a line equipped with a meter, means for extending calls of three classes from said line, means responsive to the answering of a call of the first class for operating said meter to register one impulse independent of the duration of the call, means responsive to the answering of a call of the second class for operating said meter to register one impulse for each unit of time consumed by the call, and means for operating said meter to register a plurality of impulses for each unit of time consumed by a call of the third class.

55 16. In a telephone system, a line equipped with a meter, means for extending calls of

three classes from said line, means responsive to the answering of a call of the first class for operating said meter in a distinctive manner, means responsive to the answering of a call of the second class for operating said meter in a different manner, and manually controlled means for operating said meter in a still different manner on calls of the third class.

17. In a telephone system, a line equipped with a meter, means for extending local calls, trunk calls, or toll calls from the line, means for operating said meter in a distinctive manner responsive to the answering of a local call, a timing device for operating said meter in a different manner responsive to the answering of a trunk call, and means for causing said timing device to operate said meter in a still different manner on toll calls.

18. In a telephone system, a subscriber's line equipped with a meter, subscriber control means for extending local or trunk calls to other subscribers or for extending calls to a toll switchboard from said line, means for operating said meter in a distinctive manner responsive to the answering of a local call, a timing device for operating said meter in a different manner responsive to the answering of a trunk call, and operator controlled means for causing said device to operate said meter in a still different manner on calls to the switchboard.

19. In a telephone system, two exchanges, a calling line in one exchange, a meter for said line, subscriber controlled means for extending calls from said line to other lines in either exchange, means responsive when a call is extended to a line at the same exchange for operating said meter to register one impulse independent of the duration of the call and means responsive when a call is extended to a line in the other exchange for operating said meter to register an impulse at predetermined intervals of time during the course of the call.

20. In a telephone system, a subscriber's line equipped with a meter, an impulse repeater, subscriber controlled means for extending local calls or toll calls from said line through said repeater, and a single timing device in said repeater for operating said meter differently depending on the class of call extended.

21. In a telephone system, a subscriber's line equipped with a meter, an impulse repeater, subscriber controlled means for extending calls from the line to other subscribers' lines or to a toll switchboard via said repeater, a timing device in the repeater for operating said meter in a distinctive manner on calls to another subscriber, and means controlled by the operator for causing said device to operate said meter in a different manner on calls to the switchboard.

22. In a telephone system, a calling line equipped with a meter, called lines, a manual switchboard, means for extending a connection from said calling line to any of said 5 called lines or to said switchboard, means responsive when a call to a particular one of said called lines is answered for operating said meter to register one impulse for the call independent of the duration thereof, means 10 responsive when a call to a different one of said called lines is answered for operating said meter to register an impulse for each unit of time during the course of the call, and means controlled by the operator when a call 15 is extended to said switchboard for operating said meter to register a plurality of impulses for each unit of time during the course of the call.

23. In a telephone system, a line, a meter 20 associated with said line, a trunk line terminating in a repeater, means for extending a call from said line over said trunk line via said repeater, an auxiliary switch associated with said repeater operable to periodically actuate said meter during the course 25 of a call, a relay in said repeater energized by current flow over the two conductors of the trunk line in series when a call is extended thereover, and means responsive when 30 the call is answered for reducing said current flow, said relay deenergizing to initiate the operation of said auxiliary switch.

24. In a connector switch, a wiper, a metering conductor, means responsive when the 35 switch is operated to a particular position for connecting a characteristic potential to said conductor, and means responsive when the connector is operated to a different position for connecting said conductor to said wiper.

40 25. In a telephone system, a trunk line comprising two conductors, a double wound relay bridged across the conductors of said trunk line, an initial operating circuit for said relay including the two windings of the 45 relay and the two conductors of the trunk line in series, and a holding circuit for said relay including one winding of the relay and the two conductors of the trunk line in parallel.

26. In a telephone system, a trunk line including two talking conductors, a relay 50 bridged across said talking conductors, means for operating said relay over the two talking conductors of the trunk line in series responsive to a call, and means for disconnecting 55 said relay from in bridge of said talking conductors, and for maintaining the relay operated over the two talking conductors of the trunk line in parallel responsive to the answering of the call.

60 27. In a telephone system, a trunk line comprising two conductors, a relay bridged across the conductors at one end of the trunk line, means for closing a bridge across the conductors at the other end of the trunk 65 line to operate said relay, means for dis-

connecting said relay from in bridge of the conductors and for connecting it instead to the two conductors in parallel, and means for connecting a source of current to the bridge at said other end of the trunk line 70 to maintain said relay operated.

28. In a telephone system, a trunk line comprising two conductors, a relay normally bridged across said conductors at one end of the trunk line, means for connecting a bridge across said conductors at the other end of the trunk line to operate said relay, means for disconnecting said relay and for connecting a second bridge across said two conductors at said one end of the trunk line, and means for connecting a source of current to said first bridge and for connecting said relay to said second bridge to maintain the 75 relay operated.

29. In a telephone system, a trunk line comprising two conductors, a relay bridged across said conductors at one end of the trunk line, an operating circuit for said relay including said two conductors in series and a bridge at the other end of the trunk line, a holding circuit for said relay including said two conductors in parallel and a source of current at said other end of the trunk line, and means for intermittently opening said holding circuit and for closing 80 an auxiliary circuit to maintain the relay 85 operated.

30. The combination with a trunk line including two conductors, of means for transmitting impulses over said two conductors in series to operate automatic switches, and means for completing a circuit over said two conductors in parallel to maintain the 90 switches in operated condition.

31. The combination with a trunk line including two conductors, of means for transmitting impulses over said two conductors in series to operate automatic switches, means for completing a circuit over said two conductors in parallel to maintain the switches in operated condition, and means for periodically interrupting said circuit without 95 releasing the switches.

32. In a telephone system, a trunk line including two conductors, automatic switches, means for transmitting impulses over the two trunk conductors in series for operating said switches to extend a call to a called line, means for answering the call, and means 100 responsive to the answering of the call for completing a holding circuit including the two trunk conductors connected in parallel for maintaining said switches in operated condition.

33. In a telephone system, a trunk line including two conductors, automatic switches, means for transmitting impulses over the two trunk conductors in series for operating said switches to extend a call to a called line, 105

means for answering the call, means responsive to the answering of the call for completing a holding circuit including the two trunk conductors connected in parallel for maintaining said switches in operated condition, and means for periodically interrupting said holding circuit during the course of the call.

34. In a telephone system, a trunk line including two conductors, means for completing a control circuit comprising said two conductors connected in series, means associated with one end of the trunk line for interrupting said circuit to control a switching operation at the other end of the trunk line, and means responsive to an additional switching operation at the other end of the trunk line for disabling said control circuit and for connecting the two trunk conductors in parallel.

35. In a telephone system, a trunk line, means for establishing a current flow over the conductors of the trunk line, means for interrupting the current flow to extend a call over the trunk line, means for answering the call, and means responsive to the answering of the call for momentarily reversing the direction of current flow over the conductors of the trunk line.

36. In a telephone system, a trunk line, means for establishing a current flow over the conductors of the trunk line, means for interrupting said current flow to extend a connection away from the trunk line, and means controlled over the connection for reversing the direction of current flow over the trunk conductors for a pre-determined interval of time.

37. In a telephone system, a trunk line, means for establishing a current flow over the conductors of the trunk line, means for interrupting said current flow to extend a connection away from the trunk line, and means controlled over the connection for transmitting a supervisory signal back over the trunk line by momentarily reversing the direction of current flow in the trunk conductors.

38. The combination with a trunk line, of means for establishing a flow of current in a particular direction over the trunk line during the setting up of a connection to a called line, means for reversing the direction of current flow over the trunk line for an interval following the response of the called party, and means responsive to said current flow reversal for placing the trunk in holding condition.

39. In a telephone system, a trunk line comprising two conductors, means for establishing a current flow over said conductors, means for interrupting said current flow to extend a call over the trunk line, means for answering the call, and means responsive to the answering of the call for reversing the direction of current flow over one of said conductors while the direction of current flow

over the other conductor remains the same as during the extension of the connection.

40. In a telephone system, a trunk line comprising two conductors, means for establishing a current flow over said conductors, means for interrupting the current flow to extend a call, means for answering the call, means responsive to the answering of the call for reversing the direction of current flow over both of said conductors, and means responsive to said current reversal for reversing the direction of current flow over one of said conductors.

41. In a telephone system, a trunk line comprising two conductors, means for establishing a current flow over said two conductors in opposite directions, means for interrupting the current flow to extend a call, means for answering the call, and means responsive to the answering of the call for reversing the direction of current flow in one of said conductors only.

42. In a telephone system, two trunk lines each comprising two conductors, means for establishing a current flow over each trunk line, means for interrupting the current flow in each trunk line to extend a call over the trunk line in tandem, means for answering the call, means responsive to the answering of the call for reversing the direction of current flow over the first trunk line, and means responsive to said current reversal for reversing the direction of current flow over the second trunk line for a pre-determined interval.

43. In a telephone system, an automatic switch, a trunk line including a metering conductor terminating in said switch, means for extending calls of two classes through said switch, means responsive to the answering of a call of one class for applying metering current to said conductor at a point in said switch, and means responsive to the answering of a call of the other class for applying metering current to said conductor at a point beyond said switch.

44. In a telephone system, a calling line, a meter individual to said line, a trunk, a source of current connected to said trunk, means for extending a connection from said line via said trunk, and means for disconnecting said current source from the trunk to operate said meter.

45. In a telephone system, a calling line, a meter for said line, a trunk, means for extending a connection from said line via said trunk, a battery having one pole connected to the near end of the trunk, a second battery having its opposite pole connected to the far end of the trunk, and means for disconnecting said second battery from the trunk to operate said meter.

46. In a telephone system, a calling line, a meter for said line, a trunk, means for extending a connection from said line via said

trunk, a battery having one pole connected to the near end of the trunk, a second battery having its opposite pole connected to the far end of the trunk, means for periodically disconnecting said second battery from the trunk, and means responsive to said disconnection for operating said meter.

47. In a telephone system, a calling line, a meter for the line, a trunk, means for extending a connection from the line over the trunk, means for maintaining a current flow over a talking conductor of the trunk to hold up the connection, means for momentarily stopping the current flow, means for preventing the release of the connection due to the stopping of the current flow, and means responsive to the stopping of the current flow for operating the meter.

48. In a telephone system, a two conductor trunk, a meter temporarily associated with one end of the trunk, a source of current connected to both trunk conductors at the other end thereof, means for intermittently disconnecting the current source from the trunk conductors, and means responsive to the disconnection of the current source for operating the meter.

In witness whereof, I hereunto subscribe my name this third day of January, A. D., 30 1929.

VICTOR S. THARP.

In witness whereof, I hereunto subscribe my name this third day of January, A. D., 1929.

35 CLARENCE E. LOMAX.
